CLAIM

The ornamental design for a forty button auxiliary telephone module, substantially as shown and described.

DESCRIPTION

FIG. 1 is a top front and left side perspective view of a forty button auxiliary telephone module, showing my new design;

FIG. 2 is a top view thereof;

FIG. 3 is a bottom view thereof;

FIG. 4 is a front view thereof, the rear view being substantially a mirror image;

FIG. 5 is a right side view thereof, the opposite side being substantially a mirror image of the side shown. The broken line showing of display screens in the keyboard faceplate of the module in FIGS. 1 and 2, and in the support facility for the telephone module in FIG. 1 is for illustrative purposes only and forms no part of the claimed design.
